UNITED STATES PATENT OFFICE.

WILLIAM MISCHLER, OF BROOKLYN, NEW YORK, ASSIGNOR TO E. G. WEBSTER AND SON, A COPARTNERSHIP.

DESIGN FOR A BORDER-SECTION.

40,609.

Specification for Design.

Patented Apr. 5, 1910.

Application filed January 29, 1910. Serial No. 540,932. Term of patent 3½ years.

To all whom it may concern:

Be it known that I, WILLIAM MISCHLER, a citizen of the United States, and a resident of the borough of Brooklyn, county of Kings, and State of New York, have invented a new, original, and ornamental Design for a Border-Section, of which the following is a specification.

The drawing shows an elevation of the border section embodying the design.

The essential features of the design are the framework 1, having the upper and lower margins 2 and 3 consisting of stem and leaf forms, both borders having the configuration of a cupid's bow; the semi-circular leaf forms 4 and 5 associated with the intermediate decoration 6; the decoration 7 with

outwardly branching leaf forms 8 and 9; the festoons 10 and 11 draped from the top of the shield 12 and the upper corners of the frame 1, the shield 12 and the surrounding wreath 13.

The design is intended especially to be applied to table-ware in which the section shown in the drawing will be repeated in the border.

I claim—

The ornamental design for a border section as shown and described.

WILLIAM MISCHLER.
